BOAT CONSTRUCTION

Edgar H. Ellinghouse, Davenport, Iowa

Application April 7, 1942, Serial No. 438,049

2 Claims. (Cl. 114—172)

The present invention relates to the art of boat building and more particularly to the construction of towboats and is more especially concerned with the propulsion and steering thereof. Among the objects of this invention are the provision of a boat of the character stated which will be easy to steer, both when going forward and when going backward; the provision of a boat having the capability of making greater speed, both forward and backward, than boats of the same class as heretofore constructed; and such further objects, advantages, and capabilities as will hereafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

As is well known, the loads of towboats are often made up of several barges hitched together and, unless these boats have a great deal of propelling power, they are unable to make progress against rapidly flowing streams. Therefore, I have increased the propulsive power of the boat by increasing the size of the wheels and by extending the wheels laterally beyond the sides of the boat. If the wheels are forced to rotate too rapidly in an attempt to increase the propulsive force thereof, the blades or buckets, in coming down, will strike the water so hard that a great deal of the driving power of the engine or engines is expended in overcoming the resistance of the water to the downward motion of the buckets. Likewise, the buckets, in moving upwardly, lift a great deal of water, if they are caused to rotate too rapidly. I therefore increased the area of the blades, constituting the buckets of the wheel. Also, the diameter of the wheel is increased so as to make the direction of travel of the blades in the water more nearly horizontal than if the wheel has a small diameter. I prefer a wheel approximately twenty-two feet (22') in diameter and twelve feet (12') in length. Then, by constructing the rear end or stern of the boat with openings for the reception of these wheels so that approximately seven and one-half feet (7 1/2') of the inner end of each wheel is within the general outline of the boat and four and one-half feet (4 1/2') extends laterally beyond the boat, I am able to have the advantage of the large wheel without the disadvantage of excessive width of the boat.

The boat may be provided with a hood or overhang extending entirely along each side thereof, as shown in solid lines in Fig. 1, or with hoods which are not the entire length, as shown by the broken lines in Fig. 1. These extensions serve to protect the wheels against breakage by coming in contact with wharves, barges, or other things which might cause their destruction, as well as furnishing support for the outer ends of the wheel axles.

In the drawing annexed hereto and forming a part hereof,

Fig. 1 represents a plan view of a towboat constructed in accordance with my invention; and

Fig. 2 represents a side elevation of the structure shown in Fig. 1, partly broken away.

Reference will now be made in greater detail to the annexed drawings for a more complete description of this invention. The body 1 of the boat is provided with the usual living quarters

2 and pilot house 3, and preferably has a hood 4 extending laterally therefrom to serve as an outside walkway for the crew and as a buffer to prevent the body and the wheels from being injured by bumping against wharves, barges, or other objects against which towboats often strike during the course of their use. Parts of the body and hood are omitted at the stern corners to form openings 5 for the reception of the wheels

6. As is customary, these wheels are mounted upon shafts, as shown at 7, to be rotated by the power unit or units. In the present instance, the power is indicated as coming from a pair of engines 8 located inside of the body of the boat. These are shown diagrammatically by broken lines, as are also the power transmission units, one from each engine to a wheel.

It is clear from Fig. 1 that the wheels 6 are mounted partly within the width of the body of the boat and partly outside thereof, but it is also clear that these wheels are mounted within the extreme limits of the hood 4 so that they are entirely protected against bumps by external objects. It is clear that each of the wheels has

its individual power unit 8 to which it is connected by flexible power transmission means, such as chains or belts. These drives are shown only diagrammatically, and it is clear that the drives can be stepped up or stepped down, as desired, to give the wheels any desired speed of rotation in accordance with the normal engine speed of the power units 8. It is also clear that the wheels may be rotated in unison or one may be rotated forwardly while the other turns backwardly, thus causing the boat to turn. In this

way, the boat can be steered or controlled in its course to a certain extent.

However, for the normal steering of the boat, I prefer to have a pair of rudders 9 for controlling the backing of the boat, and a pair of rudders 10 for controlling the direction of the forward running of the boat. The rudders 9 are connected by a tie rod 12. The cable 13 is wound around the drum of the steering wheel 14, and its two ends pass backwardly under the deck, as shown in Fig. 2, to the pulleys 15 and 16 about which they pass to be connected at 18 to the tie rod 11, being crossed as indicated at 17. The two ends of the tie rod 11 are connected to the two tiller rods 19 by means of which the position of the rudders 9 is controlled. The rotation of the wheels 6, when backing, throws water against the rudders 9 and, when these are set to the right or left, the force of the water against the rudders tends to turn the back of the boat in the direction in which the rudders are turned.

In a similar manner, the cable 21 is wound about the drum of wheel 22 and extends downwardly about pulleys 23 and from here rearwardly about the pulleys 24 and 25, from which the ends of the cable extend and are attached, as indicated at 26 and 27, to the tie rod 12, being crossed at 28. Therefore, when the wheel 22 is turned, the cable 21 causes movement of the tie rod 12, connected at its respective ends to the tiller arms 29 of the rudders 10. This sets the rudders to the right or left, depending upon the direction the wheel 22 is turned.

It is necessary, when backing, to lock the rudders 10 so that they will not swing from side to side in an undesired manner and, for this purpose, locking means is provided. This comprises a plurality of pins 30, 31, 32 securely set into or attached to the tie rod 12 so that they will stand all of the necessary strain connected with this operation of the boat. The latching means also includes the latch 33 pivoted at 34 upon the deck of the boat. In order to enable the pilot to unlatch the rudders 10 for steering purposes when he decides to go forwardly, a cable 35 is attached to the latch member 33 and extends forwardly and up into the pilothouse where it is suitably secured within the reach of the pilot. A pull upon this cable 35 will lift the latching member 33 away from the pins on the tie rod 12 and permit this to move longitudinally so as to shift the rudders.

The normal waterline is indicated by the broken line 36 which shows that, when the boat is standing still, the entire rudders are not immersed. However, when the wheel is turning, enough water is raised thereby so that the full faces of the rudders affected are impinged by the moving water. When the wheels turn forwardly, driven by the motors 8, the latching member 33 being released, the boat will move forwardly and may be steered by the rudders 10, controlled by the wheel 22. The rudders 9 being free to turn will assume a position substantially parallel to the direction of motion of the boat, and they do not need to be controlled, the direction of the boat being controlled by the rudders 10. When backing, the rudders 10 are set in straight-ahead position and

the latching member 33 is dropped down to engage the tie rod 12 on opposite sides of the pin 31. The wheel 14 is then operated to turn the rudders 9 to guide the boat while the wheels are driven reversely.

As the power of the motors is transmitted to the wheels, the speed thereof must be reduced, and this may be accomplished in any one of several ways. For example, the motor shaft may have a worm drive gearing rotating the shaft upon which the sprocket wheel 38 is mounted. This latter is connected by a chain 37 to a sprocket wheel 39 on the shaft 7. Thus, the speed is reduced twice, once by the worm gearing and 15 once by the difference in the sizes of the sprocket wheels 38 and 39.

Towboats are customarily equipped at their forward end with posts, as indicated at 40. The hood may end rearwardly from the front end of the boat, as shown by the broken lines 41.

While I have disclosed herein what is now regarded as the preferred embodiment of this invention, it is of course understood that this specific disclosure may be departed from without departing from the spirit of my invention as expressed in the following claims.

Having now described my invention, I claim:

1. A boat having two pairs of rudders and a pair of propulsion wheels, the propulsion wheels being set into the stern of the boat and projecting laterally somewhat beyond the sides of the hull of the boat, one rudder in front of and one to the rear of each wheel and in approximately central alignment therewith, actuating means 30 for the rearwardly located rudders connecting them for simultaneous operation, said means connecting the rudders being rigid, and means manipulable from the pilot-house to latch the rudders against lateral swinging or to release them 35 for such motion, said latching means comprising a rigid arm pivotally mounted upon the hull of the boat and pins carried by the rigid means connecting the rudders, said arm swinging in an approximately vertical plane to be positioned 40 between the pins to hold the rudders stationary or to be removed from between the pins whereby to make possible steering action of the rudders.

2. A boat having two pairs of rudders and a pair of propulsion means, the propulsion means being set into the stern of the boat, one rudder in front of and one to the rear of each of said means and in approximately central alignment therewith, actuating means for the rearwardly located rudders connecting them for simultaneous operation, said means connecting the rudders being rigid, and means manipulable from the pilot-house to latch the rudders against lateral swinging or to release them for such motion, said latching means comprising a rigid arm pivotally mounted upon the hull of the boat and pins carried by the rigid means connecting the rudders, said arm swinging in an approximately vertical plane to be positioned between the pins to hold the rudders stationary or to be removed from 55 between the pins whereby to make possible steering action of the rudders.
